US0D1016429S

(12) United States Design Patent (10) Patent No.: US D1,016,429 S
(45) Date of Patent: * Mar. 5, 2024

(54) CONNECTOR

(71) Applicant: Tamara & Bernadette Designs LLC,
New York, NY (US)

(72) Inventor: Tamara Koen, New York, NY (US)

(73) Assignee: TAMARA & BERNADETTE
DESIGNS LLC, New York, NY (US)

() Term: 15 Years

(21) Appl. No.: 29/728,453

(22) Filed: Mar. 18, 2020

(51) LOC (14) Cl. 02-07

(52) U.S. Cl.

USPC D2/624

(57) CLAIM

The ornamental design for a connector, as shown and described.

DESCRIPTION

FIG. 1 is a perspective view of a connector in the open position showing the new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a side view of the connector in the closed position.

In the drawing views, the even broken lines represent portions of the connector that form no part of the claimed design.

1 Claim, 5 Drawing Sheets
